UNITED STATES PATENT OFFICE.

GEORGE BERNHARDT DAMON, OF GLENSIDE, PENNSYLVANIA.

GAS-BURNER FOR HEATING PURPOSES.

971,429.

Specification of Letters Patent Patented Sept. 27, 1910.

Application filed November 23, 1908. Ser. No. 463,978.

To all whom it may concern:

Be it known that I, GEORGE B. DAMON, of Glenside, in the county of Montgomery and in the State of Pennsylvania, have invented 5 a certain new and useful Improvement in Gas-Burners for Heating Purposes, and do hereby declare that the following is a full, clear, and exact description thereof.

My invention relates to an improvement 10 in burners, and especially burners which are used for burning gas for heating purposes, such as in power plants.

Although my burner is applicable to the burning of an inflammable gas of any character, it has been especially designed for use 15 in connection with the burning of producer gas.

It has been extremely difficult in the past to secure an efficient producer gas burner, 20 owing to the fact that such a small proportion of air is required for combustion that it is exceedingly difficult to secure an intimate mixture of the air with the gas. The burners which have been used for this purpose 25 previously, admitted an excessive amount of air to compensate for the lack of homogeneity obtained in the mixture. This resulted in a marked lowering of the 30 temperature of the flame, as the excess of air was of necessity heated during the process of burning the combustible mixture. My burner has been designed to avoid this 35 difficulty, and in its operation a perfect mixture of a minimum quantity of air with a given quantity of fuel gas is continuously and uniformly obtained throughout its operation. These results I obtain in general by 40 directing the streams of air and fuel gas in opposition to each other, thus producing a very intimate mixture of the two, and arranging the parts in such a way that almost any element thereof can be adjusted so as to locate it in the most efficient position to obtain the best results.

45 I have shown one embodiment of my invention in the accompanying drawings, in which,

Figure 1 is a longitudinal transverse section of the burner taken on line 1—1 of Fig. 50 2; Fig. 2 is a transverse section taken on line 2—2 of Fig. 1; Fig. 3 is a transverse section taken on line 3—3 of Fig. 1; and Fig. 4 is a longitudinal vertical section of a frag-

ment of the burner taken on line 4—4 of Fig. 2 partly in elevation.

55 In the drawings, 1 is a burner barrel, or outer casing, having located at its rear a flange 2 which is adapted to be bolted to a head 3 by means of bolts 4. This head is provided with a central aperture for the passage of a main fuel gas pipe 5 and two diametrically opposed smaller openings for two steam pipes 6 located on opposite sides of the pipe 5. The head 3 is also provided with a plurality of air inlets 7 which permit air to enter into the body of the barrel or casing 1, screw-threaded so that a number of them may be plugged if necessary. The steam pipes 6 terminate within the head 3. The fuel gas pipe 5, on the contrary, passes 70 into the interior of the casing 1 to approximately the center thereof, where a hollow head 8 is attached to it. The head 8 is closed at the front by an imperforate plate 9 and is provided at its rear with a plurality 75 of peripherally located apertures or jet openings 10. The diameter of the hollow head 8 is somewhat smaller than the diameter of the bore of the casing 1, so as to leave room for the passage of the mixed gas and air 80 around the hollow head to the front of the burner casing, and the hollow head 8 is caused to be supported in a concentric position by means of the projections 11 of which there are four located around the periphery 85 of the hollow head. The pipe 5, carrying the hollow head 8, is adjustable longitudinally in the barrel 1. The pipe 5 has situated upon it a cone 12, rendered adjustable thereon by means of a tightening screw 13 90 passing through one side thereof.

In the front of the burner I provide a mixing or jet member having a tapering opening 14, which is designed to be adjustable within the barrel of the burner 1, and in 95 which it may be secured in any desired position in any suitable manner by means of screws.

In the operation of the device, the cone 12, the pipe 5 and its attached hollow head 8 100 and the member 14 are adjusted in their most efficient positions. Fuel gas, preferably producer gas, is then led into the burner through pipe 5, whence it passes into the body of the hollow head 8 and escapes through the peripheral jet openings 105 10

into the restricted portion of the burner, 1
acting as a mixing chamber, situated be-
tween the adjacent faces of the hollow head
8 and the cone 12. Simultaneously with the
5 entry of gas in this manner, steam is led
into the rear of the burner from pipes 6, air
as a consequence being entrained by the
steam and carried into the burner through
the apertures 7. The steam and air pass
10 around the periphery of the cone 12 into the
mixing chamber above referred to. At this
point the current of mixed steam and air
meets the oppositely moving jets of fuel
gas, and as a consequence a thoroughly ho-
15 mogeneous mixture of these fluids is pro-
duced. After this has taken place, the com-
bustible mixture passes to the front of the
burner around the sides of the hollow head
8 and the mixture is once more subjected to
20 a mixing and jet forming action by being
led through the hollow member 14. The
combustible mixture after passing through
the member 14 is carried to the front end of
the burner casing 1 and is burned.
25 Although I have arranged the parts in
my burner in such a way that they are ad-
justable with relation to one another, never-
theless the burner can be constructed, if so
desired, with all the parts fixed or non-
30 adjustable when once the proper position
of the various parts has been ascertained,
for any gas having an unvarying composi-
tion. It will also be seen that numerous
35 changes can be made in the construction and
location of the various parts without de-
parting from the spirit of my invention.

Changes might be made in the manner of
operation of the burner, and among such
changes it is to be understood that the pipes
40 6 might be used as means for providing a
supply of compressed air instead of a sup-
ply of steam. In this case, the openings 7
could be readily used to regulate the entire
45 amount of air supplied by obstructing one
or more of them.

I claim:

1. In a device of the character described,
the combination of a burner barrel having
an air inlet, a steam inlet and an initial
50 mixing chamber therein, said mixing cham-
ber having a substantially annular inlet for
the air and steam, and means for injecting
into said mixing chamber in an opposite di-
rection to the current of air and steam a
55 current of fluid fuel.

2. In a device of the character described
the combination of a burner barrel, a gas
inlet pipe having a head located within the
barrel provided with rearwardly directed
60 openings, a head on the rear of the burner
barrel provided with a plurality of openings
and a partial obstruction located in the rear
of the head upon the pipe to produce a mix-
ing chamber within the burner barrel.

3. In a device of the character described 65
the combination of a burner barrel, a gas
inlet pipe having a head located within the
barrel provided with rearwardly directed
openings, a head on the rear of the burner
barrel provided with a plurality of openings 70
for air, means for admitting a supply of
steam in the rear of the burner barrel and a
partial obstruction located in the rear of the
head upon the pipe to produce a mixing
chamber within the burner barrel. 75

4. In a device of the character described
the combination of a burner barrel, a gas
inlet pipe having a head located within the
barrel provided with rearwardly directed
openings, a head on the rear of the burner
80 barrel provided with a plurality of openings,
a partial obstruction located in the rear of the
head upon the pipe to produce a mixing
chamber within the burner barrel and a
member with a tapering opening in 85
the front of the burner barrel.

5. In a device of the character described
the combination of a burner barrel, a gas
inlet pipe having a head located within the
barrel provided with rearwardly directed 90
openings, a head on the rear of the burner
barrel provided with a plurality of open-
ings for air, means for admitting a supply
of steam in the rear of the burner barrel, a
partial obstruction located in the rear of the 95
head upon the pipe to produce a mixing
chamber within the burner barrel and a
member with a tapering opening in the front
of the burner barrel.

6. In a device of the character described 100
the combination of a burner barrel, a longi-
tudinally adjustable gas inlet pipe having a
head located within the barrel provided
with rearwardly directed openings, a head
105 on the rear of the burner barrel provided
with a plurality of openings and a partial
obstruction located in the rear of the head
upon the pipe to produce a mixing chamber
within the burner barrel.

7. In a device of the character described 110
the combination of a burner barrel, a longi-
tudinally adjustable gas inlet pipe having a
head located within the barrel provided
with rearwardly directed openings, a head
115 on the rear of the burner barrel provided
with a plurality of openings for air, means
for admitting a supply of steam in the rear
of the burner barrel and a partial obstruc-
tion located in the rear of the head upon
the pipe to produce a mixing chamber between 120
the head and the partial obstruction within
the burner barrel.

8. In a device of the character described
the combination of a burner barrel, a longi-
tudinally adjustable gas inlet pipe having a 125
head located within the barrel provided
with rearwardly directed openings, a head
on the rear of the burner barrel provided

with a plurality of openings, a partial obstruction located in the rear of the head upon the pipe to produce a mixing chamber between the head and the partial obstruction within the burner barrel and a member with a tapering opening in the front of the burner barrel.

9. In a device of the character described the combination of a burner barrel, a longitudinally adjustable gas inlet pipe having a head located within the barrel provided with rearwardly directed openings, a head on the rear of the burner barrel provided with a plurality of openings for air, means for admitting a supply of steam in the rear of the burner barrel, a partial obstruction located in the rear of the head upon the pipe to produce a mixing chamber between the head and the partial obstruction within the burner barrel and a member with a tapering opening in the front of the burner barrel.

10. In a device of the character described the combination of a burner barrel, a longitudinally adjustable gas inlet pipe having a head located within the barrel provided with rearwardly directed openings, a head on the rear of the burner barrel provided with a plurality of openings and a longitudinally-adjustable partial obstruction located in the rear of the head upon the pipe to produce a mixing chamber between the head and the partial obstruction within the burner barrel.

11. In a device of the character described the combination of a burner barrel, a longitudinally adjustable gas inlet pipe having a head located within the barrel provided with rearwardly directed openings, a head on the rear of the burner barrel provided with a plurality of openings for air, means for admitting a supply of steam in the rear of the burner barrel and a longitudinally adjustable partial obstruction located in the rear of the head upon the pipe to produce a mixing chamber between the head and the partial obstruction within the burner barrel.

12. In a device of the character described the combination of a burner barrel, a longitudinally adjustable gas inlet pipe having a head located within the barrel provided with 50 rearwardly directed openings, a head on the rear of the burner barrel provided with a plurality of openings, a longitudinally-adjustable partial obstruction located in the rear of the head upon the pipe to produce a 55 mixing chamber within the burner barrel and a member within a tapering opening in the front of the burner barrel.

13. In a device of the character described the combination of a burner barrel, a longitudinally adjustable gas inlet pipe having a head located within the barrel provided with rearwardly directed openings, a head on the rear of the burner barrel provided with a plurality of openings for air, means for ad-

mitting a supply of steam in the rear of the burner barrel, a longitudinally-adjustable partial obstruction located in the rear of the head upon the pipe to produce a mixing chamber within the burner barrel and a member with a tapering opening in the front of the burner barrel. 65 70

14. In a device of the character described the combination of a burner barrel, a longitudinally adjustable gas inlet pipe having a head located within the barrel provided with rearwardly directed openings, a head on the rear of the burner barrel provided with a plurality of openings, a partial obstruction located in the rear of the head upon the pipe to produce a mixing chamber within the burner barrel and a longitudinally-adjustable member with a tapering opening in the front of the burner barrel. 75 80

15. In a device of the character described the combination of a burner barrel, a longitudinally adjustable gas inlet pipe having a head located within the barrel provided with rearwardly directed openings, a head on the rear of the burner barrel provided with a plurality of openings for air, means for admitting a supply of steam in the rear of the burner barrel, a partial obstruction located in the rear of the head upon the pipe to produce a mixing chamber within the burner barrel and a longitudinally-adjustable member with a tapering opening in the front of the burner barrel. 95

16. In a device of the character described the combination of a burner barrel, a longitudinally adjustable gas inlet pipe having a head located within the barrel provided with rearwardly directed openings, a head on the rear of the burner barrel provided with a plurality of openings, a longitudinally-adjustable partial obstruction located in the rear of the head upon the pipe to produce a mixing chamber within the burner barrel and a longitudinally-adjustable member with a tapering opening in the front of the burner barrel.

17. In a device of the character described the combination of a burner barrel, a longitudinally adjustable gas inlet pipe having a head located within the barrel provided with rearwardly directed openings, a head on the rear of the burner barrel provided with a plurality of openings for air, means for admitting a supply of steam in the rear of the burner barrel, a longitudinally-adjustable partial obstruction located in the rear of the head upon the pipe to produce a mixing chamber within the burner barrel and a longitudinally - adjustable member with a tapering opening in the front of the burner barrel.

18. In a device of the character described, 125 the combination of a burner barrel, a longitudinally adjustable gas inlet pipe having a head on the inner end thereof, an adjustable

cone slidably carried upon the gas-inlet pipe, an adjustable jet or mixing member in the front of the burner barrel, and means for providing a supply of air at the rear of the burner barrel, the head on the gas inlet pipe being provided with jet orifices directed in opposition to the inflowing current of air.

In testimony that I claim the foregoing I have hereunto set my hand.

GEORGE BERNHARDT DAMON.
